Henry J. Talge and Foster L. Talge

Application August 31, 1946, Serial No. 132,997

Term of patent 14 years

(Cl. D81—10)

To all whom it may concern:

Be it known that I, Henry J. Talge, a citizen of the United States, residing at Kansas City, in the county of Jackson and State of Missouri, have invented a new, original, and ornamental Design for a Broiler, of which the following is a specification, reference being had to the accompanying drawing, forming part thereof, in which:

Fig. 1 is a top plan view of a broiler showing my new design, and

Fig. 2 is a side elevational view of the broiler shown in Fig. 1.

I claim:

The ornamental design for a broiler, substantially as shown.

HENRY J. TALGE.
